US00D803704S

(12) **United States Design Patent** (10) Patent No.: **US D803,704 S**
(45) Date of Patent: **** Nov. 28, 2017**

(54) **SENSORS**

(71) Applicant: **SICK AG**, Waldkirch (DE)
(72) Inventors: **Adrian Schwarz**, Waldkirch (DE);
Omar Saycon, Singapore (SG); **Tun Tun Lin**, Singapore (SG); **Shinde Geeta**, Singapore (SG); **Victor Phay Kok Heng**, Singapore (SG)

(73) Assignee: **SICK AG**, Waldkirch (DE)

(**) Term: **15 Years**

(21) Appl. No.: **29/556,821**

(22) Filed: **Mar. 3, 2016**

(30) **Foreign Application Priority Data**

Oct. 5, 2015 (EM) 002810838-0002

(51) **LOC (10) Cl.** **10-04**

(52) **U.S. Cl.**
USPC **D10/49**

(58) **Field of Classification Search**

(57) **CLAIM**

The ornamental design for sensors, as shown and described.

DESCRIPTION

FIG. 1 is a perspective view for sensors;

FIG. 2 is a front view of the design thereof;

FIG. 3 is a back view of the design thereof;

FIG. 4 is a right view of the design thereof, on an enlarged scale;

FIG. 5 is a left view of the design thereof, on an enlarged scale;

FIG. 6 is a top view of the design thereof; and,

FIG. 7 is a bottom view of the design thereof.

The broken lines shown in the respective Figures are for illustrative purposes and do not constitute part of the claimed design.

1 Claim, 7 Drawing Sheets
